Conn., a corporation of Delaware

Application March 23, 1950, Serial No. 151,507

4 Claims. (Cl. 60—39.65)

1

This invention relates to combustion chambers especially adapted for gas turbine power plants. The copending application of Highberg, Serial No. 150,973 filed March 21, 1950, discloses a type of combustion chamber in which the normally small length-to-width ratio is increased to a more efficient ratio by providing a plurality of parallelly positioned combustion spaces arranged in side-by-side relation in the combustion chamber such that each space has a relatively large length-to-width ratio. The parallelly arranged combustion spaces provide for a flow of primary and secondary air adjacent to the walls of the combustion chamber externally of the spaces and also between the spaces substantially centrally of the gas passage. A feature of the present invention is an arrangement for dividing the air flow between the outer passages adjacent the walls of the duct and the centrally located air passage. In this way the air flow is divided upstream of the combustion spaces in such a manner as to assure best combustion within the spaces.

The fuel and air are preferably mixed and burned before the mixture reaches the turbine thereby preventing excess temperatures from occurring within the turbine. A feature of the invention is an arrangement for causing the fuel and air to mix at a point close to the upstream end of the combustion space in order that combustion will be completed within the limits of the space. Another feature is an arrangement which will tend to produce a reverse flow of the primary air adjacent the upstream end of the combustion space thereby more effectively mixing the fuel and air and improving the combustion characteristics.

One feature of the invention is the provision, in a multiple fuel nozzle burner of individual cups in which the nozzles are positioned to assist in the mixing of air and fuel, the cups facing in a downstream direction. Another feature is the association with the cups of swirl vanes surrounding the nozzle which cause the air flowing through the vanes to swirl within the cup and thereby to follow the inside surface of the cup for additionally improving the combustion characteristics particularly in connection with the reverse flow of air above referred to.

One feature is the arrangement of the inlet air openings in the shields which define combustion spaces for suitably mixing the air with the fuel in the proper portions for best combustion and subsequently mixing the products of combustion with the secondary air flowing through the combustion chamber around and centrally of the combustion spaces.

2

Other objects and advantages will be apparent from the specification and claims, and from the accompanying drawings which illustrate an embodiment of the invention.

Fig. 1 is a longitudinal sectional view through a part of a gas turbine power plant showing the combustion chamber.

Fig. 2 is an enlarged view of a portion of the combustion chamber on substantially the same plane.

Fig. 3 is a transverse sectional view through the combustion chamber substantially along the line 3—3 of Fig. 1.

Fig. 4 is a greatly enlarged perspective view of the inlet end of a part of a combustion chamber.

Fig. 5 is a fragmentary sectional view on line 5—5 of Fig. 3.

The invention is shown in connection with a gas turbine power plant in which the compressor 2, the last stage only of which is shown, delivers air under pressure to an annular duct 4 in which fuel is mixed with the air and burned to produce power gases which are then discharged through a turbine nozzle 6 for driving the turbine rotor 8. This rotor, only a part of which is shown, is connected to the compressor rotor 10 by a sleeve 12 which may be supported in spaced bearings 14 and 16 within the supporting structure 18.

The compressor casing 20 which carries stationary vanes 22 has attached thereto at its downstream end the diffuser section 24 of the combustion chamber. This diffuser section provides an annular passage from the compressor casing and consists in diverging inner and outer walls 26 and 28 which, adjacent their upstream ends are spaced apart and parallel and are interconnected by radially extending members 30 which function as straightening vanes. These walls diverge in a downstream direction and form with the compressor casing 20 a part of a load carrying structure of the power plant. The supporting structure 18 for the bearings 14 and 16 is carried by radially extending members 30 welded or otherwise attached to the diffuser section.

The central part of the combustion chamber downstream of the diffuser section is enclosed within an outer cylindrical wall 34. The upstream end of the wall 34 is bolted to an extension of outer wall 28 of the diffuser section as by bolts 40. The downstream end of the wall 34 has a cylindrical extension 42 somewhat smaller than wall 34 and surrounding the turbine.

Within the wall 34 and supported thereby in closely spaced relation is an annular heat shield

46 which, in effect, forms a continuation of the outer wall of the duct 4. The shield 46 becomes smaller in diameter at its downstream end where it joins a second shield 48 extending diagonally inwardly to engage with the outer wall of the turbine nozzle 6, this shield 48 forming in effect a further continuation of the outer wall of the duct 4.

From the downstream end of the inner wall 26 of the diffuser section there extends a sleeve 54, the upstream end of which is connected as 54, the upstream end of which is connected as by bolts to the end of wall 26. The sleeve becomes slightly smaller at its downstream end but is nearly parallel to the wall 34. The sleeve 54 is attached at its lower end to a frusto-conical casing member 55 which becomes gradually larger in diameter to cause inner wall of duct 4 to converge toward the outer wall 34. The downstream end of member 55 engages with the inner wall of the turbine nozzle 6. Sleeve 54 is shielded from the heat within the combustion chamber by a liner 56 closely spaced from and on the outside of the sleeve 54 and member 55 is shielded by a shield 57. The duct 4 thus includes the diffuser section in which the inner and outer walls diverge, the substantially cylindrical section in which the combustion takes place, and the section of gradually decreasing cross sectional area for guiding the hot power fluid to the turbine nozzle.

The invention is shown in conjunction with a can-annular combustion chamber construction in which the duct 4 is annular and concentric to the axis of the compressor and turbine while the individual burner cans 58 are arranged in a ring around the axis of the turbine and parallel thereto, being spaced apart angularly within the annular duct. Each burner can includes an outer substantially cylindrical shield 60 the diameter of which is slightly less than the radial dimension of the annular duct to provide an air space 62 between the shield 60 and the annular heat shield 46 and also to provide an air passage 64 between the shield 60 and the liner 56.

Mounted within the cylindrical shield 60 and substantially concentric thereto is an inner shield 66 which provides a central air passage 68 the downstream end of which is closed at a point upstream of the turbine nozzle.

The inner and outer shields 60 and 66 are held in spaced relation to each other by an annular cap 70 which closes the upstream end of the space between the shields and which supports a plurality of cups 72 with their bases facing upstream and with the open ends of the cups coinciding with openings 74 in the cap 70. A fuel nozzle 76 is supported centrally within the base of each cup and the nozzle is surrounded by shrouded swirl vanes 78 which are adapted to impart a tangential swirl to the air passing over the vanes and between the nozzle and shroud 79 into the cup, to cause it, by centrifugal force, to follow the inside surface of the cup and also to produce a cylinder of moving air as it progresses down the stream. The cap 70 carries a number of these fuel injection cups each of which supports a fuel nozzle 76 with the result that the flame tube which is the annular space between the shields 60 and 66 is provided with fuel at uniformly spaced points around its circumference thereby assuring a fairly uniform distribution of the combustion within the combustion space.

Only a small amount of air enters the flame tube past the swirl vanes 78, the greater part of the primary air entering the tube through openings 80 in the outer shield 60 and similar open-

ings 82 in the inner shields 66. In the arrangement shown the openings 80 are arranged in spaced parallel rows and these openings may be in direct radial alignment with openings 82 in the inner shields. The air enters the flame tube through the openings 80 and 82 in a substantially radial direction but because of the reduced pressure within the swirling air discharged from the fuel injection cups 72 the primary air entering at least the first row of inlet openings tends to flow in a substantially upstream direction against the fuel being injected by nozzles 76 with the result of improved mixing and rapid combustion. Toward the downstream end of the shield 60 it may be advantageous to provide elongated slots 84 for the rapid admission of secondary air to mix with the products of combustion. It will be apparent that the effect of the centrally located shields 66 is to reduce the effective width of the combustion chamber, since the effective dimension is now the spacing between the shields 60 and 66, without in any way reducing the length of the flame tube so that the resulting ratio of length-to-width is increased to a more effective ratio for best combustion.

The cups 72 are in effect large angle diffusers and the swirl action assists the air in following the inside walls of the cups, thereby preventing the flow from breaking away from the walls. The diffuser action results in a low pressure directly downstream of the swirl vanes 78 and a higher pressure with lower velocity at a point approximately in line with the first row of openings 80. This higher pressure causes a flow toward the low pressure area, directly against the fuel sprayed from the nozzle. Moreover, the swirling air is provided by centrifugal force with a pressure differential such that the air has a higher pressure at the rim of the cup and a decreasing pressure from the rim toward the axis of the cup. This pressure differential assists the air flow entering the openings 80 in penetrating this swirling air so that the air from the openings 80 may reach the central part of the combustion space.

The circumferential spacing of the openings 80 is such as to provide approximately triangular areas of substantial size between the air jets directed into the combustion space from the openings 80. As a result the air which had initially moved in an upstream direction within the combustion space, and the fuel mixed with the air, and in which burning is occurring, can and does when reversed in direction adjacent the open end of the cup flow downstream through these areas without interfering with the entry of primary air to the combustion spaces.

Instead of attaching the outer rim of the cap 70 directly to the outer shield 60, a wiggle strip 86 spaces the cap from the shield and permits a flow of air longitudinally along the inner surface of the shield for cooling the shield when combustion is taking place. A similar wiggle strip 88 may be provided between the downstream end of the shield 60 and the collector ring 90 which, as shown, fits between the converging walls at the downstream end of the combustion chambers adjacent to the turbine. The wiggle strip 88 allows cooling air to flow over the inner surface of the member 90 for cooling purposes.

For the purpose of assuring the proper distribution of primary air between the outer air passages 62 and 64 and the central air passage 68, the inlet end of the combustion chamber has a dividing member 92 which has an inner wall 94 extending forwardly from the inner shield 66

and an outer wall 96 extending in an upstream direction from the outer periphery of the cap 70. The inner and outer walls merge at their upstream ends as shown and by suitable proportioning of the dimensions of the inner wall 94 and the location of the upstream end of the member 92 with respect to the surrounding diffuser section, it is possible to accurately proportion the air flow so that the air is introduced through the openings 80 and 82 to best advantage. It may be noted that another function of the walls 94 and 96 is to enclose the fuel manifolding 98 for the nozzle 76 and to streamline the air flow into the burner.

The inner wall 94 may be made up of separate elements 94a and 94b with the downstream end of the element 94a slightly larger than the adjacent end of the element 94b to provide a metering orifice 99 which controls the amount of air entering the space between walls 94 and 96 and thus controls the amount of air delivered through the swirl vanes 78 into the cups 72.

Each of the individual cans is supplied with fuel from a surrounding manifold structure 100 located externally of the diffuser section of the burner and having a substantially radially extending inwardly projecting arm 102 provided with fuel passages 104 and 106 through which fuel is admitted to the manifold 98 above referred to.

In addition to the inner and outer walls 94 and 96 of the dividing member 92, this member also has flanges 108 extending in a circumferential direction with respect to the burner duct, to engage with supporting struts 110 positioned radially between the upstream ends of adjacent burner cans, as shown in Fig. 5. With these flanges in place the desired proportion of air is delivered to the space radially inward of the flanges and also to the space radially outward thereof.

It is to be understood that the invention is not limited to the specific embodiment herein illustrated and described, but may be used in other ways without departure from its spirit as defined by the following claims.

I claim:

1. In a burner construction, an annular duct having an inlet at one end and an outlet at the opposite end for the flow of air therethrough, a plurality of cylindrical shields parallelly arranged within the duct, said shields being spaced from the duct walls and from each other to provide air passages therebetween, a tube-shaped inner shield within each cylindrical shield and defining with each cylindrical shield a substantially annular combustion space of large length-to-width ratio, an annular closure at the upstream end of each combustion space, each closure having a plurality of openings therein, said openings being filled with a fuel nozzle assembly including a downstream facing cup-shaped element, a fuel nozzle within the base of the cup-shaped element and a plurality of vanes surrounding said nozzle and surrounded by said cup-shaped element, said vanes imparting a tangential swirl to the air entering said combustion space through said vanes, said cylindrical shields and said inner shields being perforated to admit air to said combustion spaces, and means upstream of each of said cylindrical shields and closures for distributing air-flow to said inner shield, said vanes and around said cylindrical shield.

2. In a burner construction, an annular duct having an inlet at one end and an outlet at the opposite end for the flow of air therethrough, a

plurality of cylindrical shields parallelly arranged within the duct, said shields being spaced from the duct walls and from each other to provide air passages therebetween, a tube-shaped inner shield within each cylindrical shield and defining with each cylindrical shield a substantially annular combustion space of large length-to-width ratio, an annular closure at the upstream end of each combustion space, each closure having a plurality of openings therein, said openings being filled with a fuel nozzle assembly including a downstream facing cup-shaped element, a fuel nozzle within the base of the cup-shaped element and a plurality of vanes surrounding said nozzle and surrounded by said cup-shaped element, said vanes imparting a tangential swirl to the air entering said combustion space through said vanes, said cylindrical shields and said inner shields being perforated to admit air to said combustion spaces, means for substantially enclosing the upstream end of each of said cylindrical shields, means for admitting air through said enclosing means to said inner shield and said vanes, said enclosing means distributing airflow to said inner shield, said vanes and around said cylindrical shield.

3. In a burner construction, an annular duct having an inlet at one end and an outlet at the opposite end for the flow of air therethrough, a plurality of cylindrical shields parallelly arranged within the duct, said shields being spaced from the duct walls and from each other to provide air passages therebetween, a tube-shaped inner shield within each cylindrical shield and defining with each cylindrical shield a substantially annular combustion space of large length-to-width ratio, an annular closure at the upstream end of each combustion space, each closure having a plurality of openings therein, said openings being filled with a fuel nozzle assembly including a downstream-facing cup-shaped element, a fuel nozzle within the base of the cup-shaped element and a plurality of vanes surrounding said nozzle and surrounded by said cup-shaped element, said vanes imparting a tangential swirl to the air entering said combustion space through said vanes, said cylindrical shields and said inner shields being perforated to admit air to said combustion spaces, a conical shield substantially enclosing the upstream end of each of said cylindrical shields, said conical shield having a central opening through which air is admitted to said inner shield and said vanes, said conical shield distributing airflow to said inner shield, said vanes and around said cylindrical shield.

4. In a burner construction, an annular duct having an inlet at one end and an outlet at the opposite end for the flow of air therethrough, a plurality of cylindrical shields parallelly arranged within the duct, said shields being spaced from the duct walls and from each other to provide air passages therebetween, a tube-shaped inner shield within each cylindrical shield and defining with each cylindrical shield a substantially annular combustion space of large length-to-width ratio, an annular closure at the upstream end of each combustion space, each closure having a plurality of openings therein, said openings being filled with a fuel nozzle assembly including a downstream facing cup-shaped element, a fuel nozzle within the base of the cup-shaped element and a plurality of vanes surrounding said nozzle and surrounded by said cup-shaped element, said vanes imparting a tangential swirl to the air entering said combustion space through said vanes,

7
 said cylindrical shields and said inner shields being perforated to admit air to said combustion spaces, a conical shield having its base facing downstream and substantially enclosing the upstream end of each of said cylindrical shields, a walled passage through said conical shield for directing air to said inner shield, said walled passage being spaced from said inner shield to admit air to said vanes, said conical shield and walled passage distributing airflow to said inner shield, said vanes and around said cylindrical shield.
